UNITED STATES PATENT OFFICE.

HERBERT G. LA SOR, OF NEW HAVEN, CONNECTICUT.

GREASE-GUN.

1,101,638.

Specification of Letters Patent. Patented June 30, 1914.

Application filed March 11, 1914. Serial No. 823,922.

To all whom it may concern:

Be it known that I, HERBERT G. LA SOR, a citizen of the United States, residing at New Haven, in the county of New Haven and State of Connecticut, have invented a new and useful Improvement in Grease-Guns; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a grease-gun constructed in accordance with my invention. Fig. 2 a view thereof in vertical longitudinal section on the line *a*—*b* of Fig. 1. Fig. 3 a view in transverse section on the line *c*—*d* of Fig. 1, showing the charging-openings closed. Fig. 4 a corresponding view showing the charging-openings opened.

My invention relates to an improvement in that class of lubricators of the syringe-type commonly known as grease-guns which are designed for the use of greases and heavy non-liquid or semi-liquid oils, the object being to produce a simple and effective grease-gun constructed with particular reference to facility of charging it.

In carrying out my invention as herein shown, I employ a tubular metal body 2 provided toward its forward end with a long longitudinally arranged charging-opening 3 and having its rear end threaded for the application to it of a head or cap 4 and its forward end threaded for the application to it of a head or cap 5 formed with a nozzle 6. The said cap 4 has a central bearing-opening 7 for a piston-rod 8 furnished at its outer end with a bowed handle 9 and provided at its inner end with a piston 10 having two yielding packing-rings 11 larger in diameter than the piston itself. The said body 2 is inclosed from end to end in a tubular metal gate or rotatable closure 12 adapted in length to abut at its ends against the inner faces of the respective knurled beads 13, 14, of the caps 4 and 5. The said tubular gate is formed toward its forward end with a charging-opening 15 corresponding in size to the charging-opening 3 aforesaid, and upon its inner end with a gripping-band 16 produced, by preference, by cross-hatching the metal. Now I wish to call attention to the fact

that the tubular body 2 is made of light stock, whereby the charging-opening 3 will be correspondingly shallow, and in fact no deeper than the thickness of the metal of the body 2, and therefore capable of being readily filled by the expansion of the packing-rings 11 which, as they are brought into registration with the said opening 3, will immediately expand into and occupy the same and press against the inner face of the tubular gate 12 so that in the operation of the piston neither air nor contained grease or oil will have any opportunity to flow around it in either direction during the transit of the piston over that portion of the device covered by the length of the charging-openings.

In using my device, the body 2 and gate 12, either or both, are turned with respect to the other so as to bring the charging-opening 15 in the tubular gate 12 into registration with the charging-opening 3 in the tubular body 2. Then after the piston has been retracted, a given quantity of grease or oil is charged into the gun, after which the body and gate, either or both, are rotated so as to close the charging-opening 3. Now when the handle 9 is operated to force the piston 10 against the grease, sufficient pressure will be developed to expand the forward packing-ring 11 so that it will fill the charging-opening 3 in the body 2, and maintain the pressure in front of the piston for the expulsion of the heavy grease or oil through the nozzle 6. On the other hand, should it be desired to charge the gun with lighter oils in the ordinary way by placing the nozzle of the gun in the oil after pushing the piston into the nozzle-end of the gun, the suction will be maintained in full effect as the piston is retracted over the charging-opening 3 because the pressure of the air being expelled, against the rearward packing-ring 11, will cause a sufficient expansion of the same to fill the charging-opening 3.

I claim:

In a grease-gun, the combination with a tubular body made of a thin stock and having a lateral charging-opening, of forward and rear caps respectively applied to the opposite ends of the said body, a tubular gate made of relatively heavy metal and interposed between the said caps and formed with a charging-opening registering with the charging-opening of the said body, an

expansible piston located within the said body and adapted to fill the charging-opening thereof when the piston is registered with any part of the said opening, a piston rod having bearing in the said rear cap, and a nozzle upon the said forward cap.

In testimony whereof, I have signed this

specification in the presence of two subscribing witnesses.

H. G. LA SOR.
